L. D. JOHNSON

Des. 149,415

CONTROL KNOB OR SIMILAR ARTICLE

Filed April 12, 1946

FIG. 1

FIG. 2

LEON D. JOHNSON INVENTOR.

BY
Bruno C. Lechner

UNITED STATES PATENT OFFICE

149,415

DESIGN FOR A CONTROL KNOB OR
SIMILAR ARTICLE

Leon D. Johnson, Sellersville, Pa., assignor to
American Machine and Metals, Inc., New York,
N. Y., a corporation of Delaware

Application April 12, 1946, Serial No. 128,558

Term of patent 7 years

(Cl. D26—1)

To all whom it may concern:

Be it known that I, Leon D. Johnson, a citizen of the United States and a resident of Sellersville, in the county of Bucks and State of Pennsylvania, have invented a new, original, and ornamental Design for a Control Knob or Similar Article, of which the following is a specification, reference being made to the accompanying drawings, forming part thereof.

Fig. 1 shows a top view of a control knob or similar article embodying my new design.

Fig. 2 is a side elevation of the same control knob.

I claim:

The ornamental design for a control knob or similar article, as shown.

LEON D. JOHNSON.
